UNITED STATES PATENT OFFICE.

RONALD ELISON CAMPBELL, OF COLUMBIA, SOUTH CAROLINA.

STOVE.

1,427,354.

Specification of Letters Patent. Patented Aug. 29, 1922.

Application filed January 10, 1920. Serial No. 350,536.

To all whom it may concern:

Be it known that I, RONALD ELISON CAMPBELL, a citizen of the United States, and residing at Columbia, Richland County, State 5 of South Carolina, have invented certain new and useful Improvements in Stoves, of which the following is a specification.

The object of the present invention is to provide an improved trash burning or wood 10 burning stove having various novel features of construction rendering it more convenient and adaptable in use than stoves of this class heretofore designed or suggested. More particularly stated, the objects of the 15 invention are, to provide a stove of this character having draft openings at the top and bottom so that the draft may be directed against the burning fuel laterally or downwardly from the top of the stove, it 20 being optional with the user to direct the draft in either direction; which is made in sections conveniently secured together so that any section may be replaced when damaged through being burned out, or for any 25 other cause, and in which, by constructing the stove with a hopper shaped ash or fire supporting bottom the operator is enabled to quickly and conveniently remove the ashes and debris from the combustion chamber 30 by simply opening a door in the bottom through which the ashes fall.

One embodiment of the invention is described below and illustrated in the accompanying drawings in which:

35 Figure 1 is a top view of the stove, the lid of the fuel inlet opening having been removed;

Figure 2 is a section on the line 2—2 of Figure 3;

40 Figure 3 is a section on the line 3—3 of Figure 1;

Figure 4 is a section on the line 4—4 of Figure 1; and

45 Figure 5 is a sectional view of a damper plate.

The stove is preferably made of sheet metal and is substantially oval in horizontal section, as illustrated, this being the common shape of stoves of this character. It 50 comprises essentially three main portions, the top 10, the side wall 11 and the bottom 12 to which the usual supporting legs 13 are secured. These three portions are so secured together as to be readily detachable. As 55 illustrated, screw bolts 14 sufficient in number for this purpose are provided, the top

having a downwardly extending flange overlapping the upper edge of the side wall and the bottom 12 having an upwardly extending flange which overlaps the lower 60 edge of the side wall, the securing bolts 14 extending through these flanges and the side wall, as illustrated in Figure 3.

The top has a flanged circular opening 15 provided with a cover 16 and through this 65 opening, when the cover is removed, the fuel may be inserted into the combustion chamber. The top is also provided with a circular opening having a flange 16^a to which the ordinary stove pipe 17 may be fitted in the 70 usual manner. A transverse metallic curtain 18 is hung by suspension rods 19 from the edge of the ring member 20, which fits closely around the flange of opening 15 and is not removable with the cover. The purpose of this curtain is to direct the draft 75 downwardly against the fuel within the combustion chamber, and also to prevent, to a large extent, the products of combustion from passing out through the fuel opening 80 15 when the cover is removed to introduce additional fuel. If desired, the member 18 may be permanently secured to the top, but preferably it is detachably hung as illustrated, so as to be readily removable. 85

The side wall of the stove is provided with a flanged opening 21 suitable for connection with a stove-pipe, and smaller flanged openings 22 and 23 which are draft openings. When the opening 16^a in the top 90 is connected to a stove-pipe, as illustrated in the drawings, the opening 21 is closed by a cover 24 as shown.

In the drawings, the elbow pipe 25 is connected to the flanged opening 22 and has its 95 upper end open for the free passage of air, while the lower draft opening 23 is closed by a circular damper plate 26. This damper plate 26 fits against the end of the short pipe section or neck 27 which is secured to the 100 flange of the opening 23 and has four spring arms 28 shaped as shown, which press outwardly against the inner wall of the flange and exert a sufficient pressure thereagainst to frictionally hold the plate in position. 105 The damper is freely removable by simply pulling outwardly on the handle, and it is obvious that a combination of drafts may be used if desired by pulling the damper 26 away from its seat a short distance. Al- 110 though I have illustrated in the drawings only one damper plate, which is interchange-

able with the elbow pipe 25, I may provide two damper plates, one for each opening, by which means any desired combination of draft air feeds to the combustion chamber 5 may be arranged.

The bottom 12 of the stove is, in the present embodiment of my invention, formed in two portions, a lower horizontal plate, and a fire or ash supporting portion formed 10 in two parts 12', 12''. These plates 12' slope downwardly toward a longitudinal opening 12² running lengthwise of the bottom plate 12 and the upper edges of these inclined portions are riveted or otherwise suitably 15 secured to the side wall 11. The opening 12² is provided for the removal of ashes and debris through the bottom of the stove and is normally closed by a sliding plate or door 29 which is manipulated by a handle 30. 20 Upon the plates 12' and the sliding door 29 the burning fuel rests and, when the fire is out and it is desired to remove the ashes, it is only necessary to move the sliding door 29 so that the opening 12² is uncovered, 25 whereupon the ashes will immediately drop into the receptacle which has been placed below the stove to receive them, the angle of inclination of the plates 12' being such that the materials on their upper surfaces will 30 slide down when unsupported from below. Hand holes 12³ are formed in plate 12 so that the bolts 14 securing the sections together may be easily reached.

Although I have described and illustrated 35 the portions 12' of the fire bottom as secured to the side wall, it is obvious that they may be conveniently secured in other ways, and as other changes may obviously be made in the arrangement of parts I do not limit 40 myself to the exact form described and illustrated. The adjustability of the draft, the adaptability of the stove to different positions because of the fact that the stove-pipe may be connected to the top or side, the 45 sectional construction, whereby any section burned out or otherwise injured may be replaced without involving the replacement of

the whole stove or any other section, and the construction which enables the user to quickly and conveniently remove the ashes 50 without the use of shovels, pushers, or other instruments, are all features which render the stove particularly useful from a practical standpoint.

Having thus described the invention what 55 is claimed as new and desired to be secured by Letters Patent is:

1. In a stove of the class described, in combination, a combustion chamber elongated in horizontal cross section, such chamber having an opening in its top for the introduction of fuel and a longitudinal central slot or opening in its bottom for the removal of ashes, two flat fuel supporting plates extending longitudinally of said chamber one 60 on each side of said opening and inclined downwardly toward the same, and an elongated sliding door for controlling the passage of ashes through said opening.

2. In a stove of the class described, in combination, a combustion chamber having an elongated horizontal cross section, said chamber having an opening in its top for the introduction of fuel and a central longitudinal slot or opening in its bottom for the 75 removal of ashes, two flat fuel supporting plates extending longitudinally of said chamber one on each side of said opening and inclined downwardly toward the same, the inner edge of the plates terminating at 80 the edges of the central opening, and the outer edges of the plates being secured to the side walls of the chamber, and an elongated sliding door for controlling the passage of ashes through said opening.

3. In a stove of the class described, a body comprising a top, side wall and bottom, and having air inlet openings in the side wall adjacent the top and bottom respectively, and a damper plate adapted to fit either of 90 said openings as desired to close the same.

In testimony whereof I affix my signature.

RONALD ELISON CAMPBELL.
